(57) **CLAIM**

The ornamental design for a drive support dolly for a hand held hot air device, as shown and described.

DESCRIPTION

FIG. 1 is a right side elevational view of a drive support dolly for a hand held hot air device showing our new design;

FIG. 2 is a left side elevational view thereof;

FIG. 3 is a front elevational view thereof;

FIG. 4 is a rear elevational view thereof.

FIG. 5 is a top plan view thereof;

FIG. 6 is a bottom plan view thereof; and,

FIG. 7 is a front perspective view thereof.

The broken lines in FIGS. 1 and 7 represent portions of the drive support dolly for a hand held hot air device that form no part of the claimed design.

1 Claim, 4 Drawing Sheets
